Inventor:

Charles F. Mooney,
By Frank C. Curtis
Attorney

UNITED STATES PATENT OFFICE.

CHARLES F. MOONEY, OF SCHENECTADY, NEW YORK.

COMPASSES.

1,235,715.

Specification of Letters Patent. Patented Aug. 7, 1917.

Application filed January 19, 1917. Serial No. 143,412.

To all whom it may concern:

Be it known that I, CHARLES F. MOONEY, a citizen of the United States, residing at Schenectady, county of Schenectady, and State of New York, have invented certain new and useful Improvements in Compasses, of which the following is a specification.

Reference may be had to the accompanying drawings, and the reference characters marked thereon, which form a part of this specification. Similar characters refer to similar parts in the several figures therein.

The invention relates to compasses adapted for various uses, and particularly to compasses used by machinists for plotting and laying out work, where angular or circular measurements are involved.

The principal object of the invention is to facilitate the determining, marking or laying off of angles, chords or arcs of required dimensions.

Other objects will appear in connection with the following description.

Figure 1 of the drawings is a view in side elevation of compasses embodying my invention.

Fig. 2 is a similar view with the legs of the compasses extended to adapt the instrument for determining, marking or laying off angles or arcs of circles of larger diameter than that for which the instrument as shown in Fig. 1 is adapted.

Fig. 3 is a view in side elevation of one of the outer leg-sections.

Referring to the drawings wherein the invention is shown in preferred form, 1 and 2 are the legs of the compasses, flexibly connected together at 3, as by a pivotal connection. Each leg of the compasses has a linear scale extending longitudinally thereof indicating in units of linear measurement distances from the axis of the pivotal connection, 3.

A scale-plate, 4, extends transversely of the legs, 1 and 2, being connected with the leg, 1, and being in sliding relation to the leg, 2, the leg, 2, being provided with a slot or opening, 5, through which the scale-plate freely passes.

The leg, 2, is also provided with a thumb-screw, 6, engageable with the scale-plate, 4, to releasably lock the same in fixed relation to the leg, 2.

The end of the scale-plate, 4, adjacent to the leg, 1, has a screw-threaded shank, 7,

which passes through a suitable aperture in the leg, 1, and is provided on its outer end with an adjusting nut, 8, which nut is provided on its inner side with a chamber, 9, adapted to receive a coil-spring, 10, interposed between the nut and the leg, 1.

A spring-plate, 11, is mounted upon the inner side of the leg, 1, in engagement with a shoulder, 12, on the scale-plate, tending to withdraw the threaded shank, 7, of the scale-plate through the leg, 1, in the direction of the leg, 2, thus tending to separate said legs.

This spring-plate, 11, is normally held fully compressed between the shoulder, 12, on the scale-plate, 4, and the leg, 1, by means of the adjusting nut, 8.

The scale-plate, 4, is marked in units of circular measurement as degrees, said markings being adapted to be read with reference to the inner edge of the leg, 2.

The inner surfaces of the legs, 1 and 2, are preferably plane surfaces in planes intersecting each other at the axis of the pivotal connection, 3.

The adjusting nut, 8, is circumferentially marked to indicate fractional parts of one of the units of circular measurement which appears on the scale-plate, 4, its marks being read in connection with an index mark, 13, on the leg, 1.

If the scale-plate, 4, is marked in degrees, and the adjusting nut, 8, bears thirty equally spaced scale-marks, one complete rotation of the adjusting nut will cause a variation of one-half degree in the angular distance between the legs, 1 and 2.

The legs, 1 and 2, are preferably made extensible, as by means of an outer leg-section, 14, adapted to telescope within the respective inner or main section of the leg, and to be secured in fixed relation thereto in the selected position of adjustment by means of set-screw, 15.

These outer leg-sections, 14, each bear linear scales, 16, extending longitudinally thereof indicating in units of linear measurement distances or lengths supplementary, or additional, to those indicated by the scale-markings on the main leg-sections, 1 and 2.

The scales on each main leg-section, 1 or 2, and the scale, 16, on the respective outer leg-section, 14, form, when the legs are fully contracted, a continuous scale indicating distances from the axis of the pivotal connection, 3.

As it is difficult to continue the scales on the outer leg-sections to the extreme outer ends thereof, I place upon one or both of the main leg-sections, 1 and 2, an indication 5 of the total length of each leg from the axis of the pivotal connection, 3, to its extreme outer end or point when the leg is fully contracted. Thus on each main leg-section I have placed the mark "6 in." indicating such 10 length to be six inches.

The shank, 17, of each outer leg-section, 14, which telescopes within the respective main leg-section, 1 or 2, is also provided with a scale adapted to be read in connection with 15 the outer end of said main leg-section to show the total length of the leg from the axis of the pivotal connection, 3, to the extreme end or point of the leg when more or less extended.

20 Each outer leg-section terminates in a tip or point, 14^a, detachably mounted upon the leg-section by means of a screw-chuck, 18, whereby points of different kinds may be used in place of the particular form of points 25 shown in the drawing.

Each outer leg-section terminates in a tip or point, 14^a, detachably mounted upon the leg-section by means of a screw-chuck, 18, whereby points of different kinds may be used in place of the particular form of points 30 shown in the drawing.

35 The instrument above described is adapted for many uses by the machinist in plotting or laying off work where angular or circular measurements are involved.

For example: Let it be required to lay out nineteen holes on a circle 14 $\frac{1}{2}$ inches in diameter. To do this, each leg is extended until the scale-reading on the shanks, 17, 40 of the respective outer leg-sections indicates 7 $\frac{1}{4}$ inches which would be the radius of said circle; and the outer leg-sections are locked in this position by means of the set-screws, 15. The legs of the compasses are then 45 spread apart until the reading on the scale-plate, 4, indicates 18 $\frac{1}{2}$ degrees in which position the leg, 2, is locked to the scale-plate by means of the thumb-screw, 6.

The adjusting-nut, 8, is then turned until 50 the reading of its circumferential scale indicates approximately 27 minutes, thus causing a slight further separation of the legs of the compasses, and causing their points to be separated approximately the distance 55 between two holes spaced as required. The compasses may then be used as dividers to lay off upon the circle the nineteen holes required.

60 For angular measurements in degrees and half-degrees the scale-plate, 4, alone will ordinarily be found sufficient. When the measurement involves a smaller fraction of a degree, the adjusting-nut, 8, may be used.

Points or holes can be also laid off on a 65 circular line at irregular spaces, it being

merely necessary to adjust the length of the legs of the compasses to correspond with the radius of the circle, and then to whatever angular degree the legs be opened, the distance between the points of the legs will in each case represent a corresponding angular distance between points on the circumference of said circle. 70

The scales on the main leg-sections make it possible to determine angular or circular 75 measurements with relation to circles having a radius less than the length of the legs of the compasses when contracted, as follows:

Let it be required to lay out sixteen 80 points or holes on a circle, the diameter of which is 8 inches. The legs, 1 and 2, are separated until the reading on the scale-plate, 4, indicates 22 $\frac{1}{2}$ degrees. The points of a pair of ordinary dividers are then stretched across the angle between the legs, 1 and 2, until one point of the dividers is located at the point of intersection of the 4-inch scale-line on the leg-section, 1, with the inner edge of said leg-section, and the other point of the dividers is located at the 85 point of intersection of the 4-inch scale-line on the leg, 2, with the inner edge of that leg.

The dividers so spaced can be then used to lay off the properly located points on the circumference of the circle. 90

In employing divider points on the legs, 95 as the points, 14^a, said points are preferably indent as shown in the drawing, so that their apices are in the respective planes of the inner side surfaces of the legs, as shown, 100 thus insuring accuracy in the use of the instrument as dividers.

What I claim as new and desire to secure by Letters Patent is—

1. An instrument of the class described 105 comprising a pair of flexibly connected legs each bearing a linear scale extending longitudinally thereof; and a scale-plate extending transversely of said legs in slidable relation to one thereof, said scale-plate being 110 marked in units of circular measurement.

2. An instrument of the class described comprising a pair of flexibly connected extensible legs each bearing a linear scale whereby its length is indicated; and a scale-plate extending transversely of said legs in 115 slidable relation to one thereof, said scale-plate being marked in units of circular measurement.

3. An instrument of the class described 120 comprising a pair of flexibly connected legs each bearing a linear scale extending longitudinally thereof; and a scale-plate extending transversely of said legs in slidable relation to one thereof, said scale-plate having a screw-threaded shank extending through the other of said legs and being 125 marked in units of circular measurement; a spring tending to withdraw said screw-threaded shank through said last-mentioned 130

leg toward the other of said legs; and an adjusting nut on the outer end of said screw-threaded shank bearing a circumferential scale indicating fractional parts of one of said units on said scale-plate.

4. An instrument of the class described comprising a pair of flexible connected extensible legs, each comprising a plurality of leg-sections, one longitudinally adjustable 10 upon the other, one of said leg-sections being

provided with an index and the other with a linear scale, indicating with reference to said index the total length of the leg; and a scale-plate extending transversely of said legs in slidable relation to one thereof, said scale-plate being marked in units of circular measurement.

In testimony whereof, I have hereunto set my hand this 13th day of January, 1917.

CHARLES F. MOONEY.
